CLAIM

The ornamental design for a combined key chain and container, as shown and described.

DESCRIPTION

FIG. 1 is a perspective view of a key combined key chain and container showing my new design;

FIG. 2 is a right side elevational view;

FIG. 3 is a front elevational view;

FIG. 4 is a top plan view;

FIG. 5 is a bottom plan view; and,

FIG. 6 is a perspective view shown with the cap removed;
The broken line showing of a hand in FIGS. 1 and 2 and of
toothpicks in FIG. 6 is for illustrative purposes only and
form no part of the claimed design.
